DRY SHAVER

Jacob Schick, Stamford, Conn.

Application September 20, 1935, Serial No. 41,385

4 Claims. (CL. 30—43)

This invention relates to an improved shaving machine, particularly machines that shave dry hair, and is designed to overcome certain disadvantages resident in former types of shaving heads.

The shaving head of a dry shaver comprises an outer shear member of rectangular or circular shape in cross-section and an inside cutter of rectangular or circular shape in cross-section movably placed inside the outer member. The two members of the assembly are slotted to form narrow blades and the movement of one relative to the other causes the blades to sever hair in the slots. The proper functioning for securing a comfortable shave depends to a great extent on an even pressure to maintain the blades or teeth of the inside cutter against the inside face of the blades of the outer member in close contact for the entire length of the shaving head. The usual device heretofore employed has been springs mounted at or near the ends of the cutters. This is satisfactory to some extent but the difficulty is in securing springs that have and maintain an even pressure. One of the springs is weaker or becomes weakened with use and one end of the inside cutter is pressed either too lightly or too strongly against the outer member. This condition, if too strong, puts too much load on the motor of the machine, or if too light allows minute ends of hair to work in space between the blades of the members, holding them apart slightly and this in turn interferes with proper clipping and the machine "pulls" when used for shaving.

The present invention is designed to provide a shaving head in which the pressure is evenly applied and is balanced whereby the pressure of the inner member against the outer member is the same for its entire length.

The invention is illustrated in the accompanying drawing. Figure 1 is a sectional view of a shaving head made according to my invention, the sectionized parts being taken on line 1—1 in Figure 2. Figure 2 is a central longitudinal section of the shaving head shown in Figure 1. Figure 3 is a section taken on line 3—3 in Figure 2. Figure 4 is a view similar to Figure 2 but showing a modified form of cutter support. Figure 5 is a cross-section showing the spring support applied to a round shaver.

The shaving head is of the usual commercial form such as in the United States Patent No. 1,747,031 granted to Jacob Schick. The particular form of shaver is not important, however, as the support is applicable to any shaver or clipper

having co-acting slotted members at least one of which is movable relative to the other. The shaving head illustrated comprises an outer member 10 which has a shear plate at the shaving end, the plate being slotted as at 11 to form narrow blades 12. The outer member has the block or base 13 at the bottom which is seated in the end of the casing 14 and is secured by suitable means such as the thumb screw 15. The movable inside cutter 16 is slotted under the shear plate, as at 17, to form cutters or teeth 18 that co-operate with the blades 12 to cut hair that enters the slots 11. This form of shaving head is well-known and in commercial use for a number of years. In addition to precision in manufacture it is necessary to establish an even pressure on the inside cutter to cause the teeth and blades to fit snugly together on their abutting faces. The movable inside cutter is operated by suitable means and I show a lever 19 that passes into a recess 20 in the inside cutter and thus moves the cutter. The base 13 has an opening at 21 and casing 14 has an opening 22 for free movement of the lever. The lever is pivoted on the stud or screw 22^a and the part 23 that extends beyond the pivot is oscillated by a suitable motor.

The invention is designed to cause a positive clipping or shaving action along the whole length of the cutting members by an equalizing device. This device comprises a spring 24 of suitable stiffness which spring can rock or tilt at the central part. The spring bears at its ends on pins 25 which pins in turn press on the bottom of the inside cutter. Any excess pressure on one end of the spring is transmitted to the other end and the two pins bear with equal pressure on the inside cutter. The pins pass loosely through the openings 26 in the casing and outer member to enable them to rock slightly as the cutter is reciprocated and the shoulders 26^a may be employed preventing undue projection of the pins or their loss when the shaving head is removed from the casing for cleaning or inspection. The spring may be hollowed as at 27 for reception of the ends of the pins 25. The spring is preferably formed into a spring loop 28 at its center for clamping it on the stud or screw 22 and still allowing freedom for the spring to rock. This overcomes the difficulty in having separate springs which difficulty is caused by the springs being of different degrees of resiliency. In some cases the difference in springs appearing to be of the same length and strength is marked as to pressure when in use and the shaving on one end of a cutter is

not as satisfactory as at the other end. In Figures 1, 2 and 3 the pins can rock slightly and preferably have rounded ends.

An alternative form is shown in Figure 4 in which the pins 29 are fixed against rocking but can slide freely in the openings 30. The form shown presents hollow pins which may be provided with a plug or wick 31 either made of lubricant or impregnated with a lubricant.

10 In Figure 5, I show the spring means as applied to a shaving head of tubular form with the outer member 31* having an eccentrically arranged inner cutter 32 with an eccentric bore 33 in it.

15 The pins will compensate for any wear on the abutting surfaces of the cutters and maintain an even pressure at all times.

I claim:

1. A dry shaver comprising an outer member, 20 an inside cutter movable in the outer member, pins bearing on the inside cutter at its ends, and a spring supported intermediate its ends and with its ends bearing on the ends of the pins whereby both ends of the inside cutter operate 25 under the same pressure.

2. In a device of the kind described, a casing,

a shearing head secured on the end of the casing, the shearing head comprising an outside cutter, an inside cutter movable inside the outside cutter, a spring supported at its centre inside the casing in a manner to allow a limited tilting and 5 posts bearing on the ends of the spring and on the under side of the inside cutter.

3. In a device of the kind described, a casing, a shearing head secured on the end of the casing, the shearing head comprising an outside 10 cutter, an inside cutter movable inside the outside cutter, a spring supported at its centre inside the casing in a manner to allow a limited tilting, and posts having a slight rocking motion 15 when the inside cutter is operated.

4. In a device of the kind described, a casing, a shearing head secured on the end of the casing, the shearing head comprising an outside cutter, an inside cutter movable inside the outside cutter, a spring supported at its centre inside the 20 casing in a manner to allow a limited tilting and posts with lubricating wicks bearing on the ends of the spring and on the under side of the inside cutter.

JACOB SCHICK. 25
